COIN OPERATED DEVICE

Linden A. Thatcher and Francis J. Rouan, Stamford, Conn., assignors to Pitney-Bowes Postage Meter Co., Stamford, Conn., a corporation of Delaware

Application May 15, 1942, Serial No. 443,050

6 Claims. (Cl. 194—54)

This invention relates to a coin operated device wherein the coin effects operation of the device while the coin is under control of the manual force applied by the operator, and further relates to control means for the prevention of fraudulent operation of the device.

In the operation of coin controlled vending machines, the usual practice is to insert a coin, then apply power through the pressure of a button or the pull of a handle to effect a cycle of machine operation. With the device according to this invention, the insertion of the coin provides the power factor for performing the operation of vending, or whatever other performance the machine is qualified to provide. In view of the fact that the vending operation is performed during the period of coin insertion, means is provided to make it extremely difficult to fraudulently manipulate the device, and further, to provide means whereby if a successful fraudulent operation is attained, an internal locking mechanism will become effective to prevent any further operation of the machine until reset by a person authorized to enter the machine.

It is the object of the invention therefore, to provide in a coin operated device, means whereby operation of the device is performed directly upon insertion of the coin; means whereby fraudulent operation is made extremely difficult; and means whereby the device is entirely locked out from within if a single performance of fraudulent operation is effected.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawing, wherein:

Fig. 1 is a sectional view through the casing of a machine, with the coin operated mechanism shown in elevation;

Fig. 2 is a front elevational view of Fig. 1;

Fig. 3 is a view similar to Fig. 1, showing the parts in an operating position at one point during the period of coin insertion;

Fig. 4 is a view similar to Fig. 1 in part, and particularly shows the normal position of the locking elements;

Fig. 5 is a sectional view taken along the line 5—5 of Fig. 1; and

Fig. 6 is a view similar to Fig. 3 in part, showing one of the locking elements in a released position during the period of coin insertion.

Application of a device of the character of this invention may be made with various types of vending or like machines, but in view of the device being particularly related to the coin controlled feature, no reference will be made to any particular class of machines for which it may be used.

Referring to the drawing, the element which is to be controlled comprises a shaft 10, best shown in Fig. 5, which shaft is supported in bearings 11—11, projecting from supporting walls 12—12. A disc 13, a ratchet toothed wheel 14, and star wheel 15 are joined together as a unit, and are fixed to the shaft 10. The disc 13 further has a plurality of evenly spaced pins 16 projecting from one face thereof, and a hub 17 on the ratchet wheel 14 has a plurality of openings 18 therein.

Associated with the star wheel 15 is a detent lever 19, pivoted on a stud 21, which has a detent portion 22 normally urged into engagement with the star wheel by means of a spring 23.

Associated with the ratchet wheel 14 is a locking lever 24, which is pivoted on a stud 20, and has a claw like portion 25 including diametrically opposed tooth projections 26—27, as best shown in Fig. 4. Said locking lever 24 is further provided with a lip portion 28, bent at right angles to the face of the lever, and has a pin 29 projecting sidewardly from one face thereof. By means of a spring 31, the locking lever 24 is normally urged to rotate in a counterclockwise direction, as viewed from Fig. 4.

A casing 32 encloses the coin control mechanism, as shown in Fig. 1, and has a coin slot 33 therein positioned in alignment with the pins 16 on the disc 13.

A novel arrangement of the device makes use of each coin after insertion and after the normal operation of the device, to provide an interponent between the lever 24 and disc 13 for the purpose of establishing a normal position for the locking lever 24. As shown in Fig. 1, the coin C, after insertion in the machine, will become lodged between the pin 29 on lever 24, and a pocket produced by a pair of pins 16 projecting from the disc 13.

A lock-out control lever 34 is associated with the locking lever 24 and detent lever 19, and is arranged to provide for the complete locking out

of the machine, if by fraudulent manipulation the interponent coin C is removed. Said lock-out control lever 34 is mounted upon a stud 35 and has two arms 36 and 37. The arm 36 is normally urged against the tail end of lever 24 by means of a spring 38, while the arm 37 normally lies in the path of the upper edge of a pointed projection 39 on the detent lever 19.

During the normal rotation of the star wheel 15, upon inserting a coin C, as in Fig. 3, the arm 37 of the lever 34 will ride upon the upper edge of the projection 39 and return to its normal position, as in Fig. 1, at the end of the stroke of the disc 13. If, however, the interponent coin should have been removed by fraudulent means, the locking lever 24 would be rocked by the force of the spring 31, to remove the tail end thereof from the path of the arm 36. This in turn, would effect rocking of the arm 37 into the path of the lower edge of the projection 39, to thereby prevent rocking movement of the detent lever 19. Permanent locking of the star wheel 15 would thus be effected until the device was readjusted by placing another interponent coin in position between the pin 29 on lever 24, and pins 16 on disc 13.

It is to be further noted that when the interponent coin is in position, as in Fig. 1, the lip 28 is in position to be engaged by the inserted coin, as in Fig. 3, when the coin passes through the slot 33, to thereby effect the camming of the lever 24 a sufficient distance above the pivot stud 20 to release the toothed projection 27 from the path of the ratchet teeth of ratchet member 14.

A coin, after being properly inserted, first engages one of the pins 16 of the disc 13 to rotate said disc and drive the shaft 10 therewith. During such rotation, the detent lever 19 is rocked about its pivot stud 21, as in Fig. 3, so as to become reengaged with the next succeeding cavity in the star wheel 15. During such rotation also, the interponent coin is released for deposit in any suitable manner therebelow, while the newly inserted coin takes the position of the interponent coin.

From the mechanism as thus far described, let us assume that someone having intention to fraudulently release the machine for operation, inserts a suitable implement through the slot 33 to engage the lip 28, and by careful adjustment is successful in obtaining the precise position required to free the toothed projection 27 from the path of the teeth of the ratchet wheel 14, while also maintaining the toothed projection 26 free of said teeth, and further is successful in rotating the disc 13. As a result of such manipulation a single operation of the device will be effected. However, during such operation the interponent coin will have been released, and the locking lever 24 will have rotated to remove the tail portion thereof from the arm 36 of lock-out lever 34. As previously stated, this will cause the arm 37 of said lock-out lever to drop behind the lower edge of the projection 39 and block further attempt to manipulate the device until proper readjustment is made by a person authorized to enter the machine.

In order to make it further difficult for anyone to fraudulently operate the device, a further locking lever 41 may be provided, as best shown in Fig. 6. Said lever 41 is suitably mounted upon the stud 20 and is urged to rotate in a clockwise direction by a spring 42. A claw like structure at the working end thereof comprises a lower

toothed arm 43 and an upper toothed arm 44. The lower toothed arm is adapted to normally lie within the path of the teeth of ratchet 14, as in Fig. 4.

If fraudulent manipulation were attempted, it would be necessary to adjust said lever 41 to the precise position shown in Fig. 6, in addition to manipulating the lever 24 to its precise position, before the disc 13 could be rotated. If the lever 41 is rocked too great a distance the toothed portion 44 will engage an opening 18, and if too little the toothed portion 43 will still be in the path of the teeth of ratchet 14.

Having described the invention, what is claimed is:

1. In a coin operated device, means whereby direct operation of the device is effected by a coin upon inserting said coin in the device, said means comprising a movable member engageable by the coin and movable a predetermined distance by the manual force applied to the coin while the coin is being inserted, obstruction means normally in locking position with relation to the movable member before inserting the coin and being movable by engagement of the coin therewith to free said movable member, a coin previously inserted forming an interponent supported between the obstruction member and movable member, detent means to inhibit the movement of the movable member, a detent locking member, means to normally urge the detent locking member toward a locking position with relation to the detent means, a stop normally retaining the detent locking member in a non-locking position, removal of said stop being adapted to be effected when fraudulent manipulation of the device is attempted in a manner which causes the interponent coin to be dislodged from its interponent position, without replacement by another coin, whereby the detent locking member is then urged to a detent locking position to prevent repeated fraudulent manipulation.

2. In a coin operated device, means whereby direct operation of the device is effected by a coin upon inserting said coin in the device, said coin replacing an interponent coin hereinafter defined, said means comprising a rotatable member engageable by the coin and movable a predetermined distance by the manual force applied to the coin while the coin is being inserted, obstruction means normally in locking position with relation to the rotatable member before inserting the coin and being movable by engagement of the peripheral surface of the coin therewith to free said rotatable member, a detent member associated with the rotatable member, means to engage a previously inserted coin so that it will act as an interponent between the obstruction means and rotatable member, a lockout member urged toward the detent member and normally engaging the obstruction means, thereby permitting the detent member to normally control a limited movement of the rotatable member when each coin is inserted, said lockout member being movable to a blocking position with relation to the detent member if the interponent coin is released by means other than the insertion of a coin and the lockout member is freed by the obstruction means.

3. In a coin operated device having a coin slot and including a rotatable element, obstructing devices and means adapted to receive a coin, the coin to form an interponent between the rota-

table element and obstructing devices; means whereby rotation of the rotatable element is effected by a second coin upon inserting the second coin in the coin slot, means to prevent fraudulent manipulation of the rotatable element including means to urge the obstructing devices into a locking relation with the rotatable element, and means forming a part of said obstructing devices lying in the paths of the upper and lower peripheries of the coin and being movable by the coin when inserting said coin, to thereby effect removal of the obstructing devices from their locking relation with the movable means, whereby fraudulent effort to manipulate the device requires delicate adjustment of each obstructing device against opposing spring pressure to the precise distance apart such as would normally be effected by a coin.

4. In a coin operated device, means whereby direct operation of the device is effected by a coin upon inserting said coin in the device, said means comprising a movable member engageable by the coin and movable a predetermined distance by the manual force applied to the coin while the coin is being inserted, means to prevent fraudulent manipulation of the movable member including a spring urged obstruction member normally positioned in locking relation with the movable member before inserting the coin, the coin previously inserted forming an interponent supported between the obstruction member and the movable member to maintain said obstruction member in proper position for engagement by a succeeding coin while in a locking position, and means cooperating with the obstruction member, whereby when engaged by a coin, the obstruction member is removed from an obstructing position and the movable member is moved the predetermined distance, and a lock-out member controlled by the obstruction member, whereby, when manipulation of the obstruction member and movable member is attempted by other than a coin the lock-out member will be released to effect the locking of the movable member against further release by a coin.

5. In a coin operated device, means whereby direct operation of the device is effected by a coin upon inserting said coin in the device, said means comprising a movable member engageable by the

- coin and movable a predetermined distance by the manual force applied to the coin while the coin is being inserted, and means to prevent fraudulent manipulation of the movable member including a spring urged obstruction member normally positioned in locking relation with the movable member before inserting the coin, the coin previously inserted forming an interponent supported between the obstruction member and the movable member to maintain said obstruction member in proper position for engagement by a succeeding coin while in a locking position, a spring urged detent member engaging the movable member and adapted to inhibit movement of the movable member, and a locking member associated with the detent member and obstruction member, whereby fraudulent manipulation of the obstruction member and movable member by other than a coin will effect movement of the locking member to a locking position with respect to the detent member to lock the movable member until released by one authorized to enter the device.
6. In a coin operated device having a coin slot and including a rotatable element, obstructing means, and means to receive a coin, said coin forming an interponent between the rotatable element and obstructing means, said rotatable element having pockets therein, one pocket lying in the path of the coin slot and being engageable by a coin to effect rotation of the rotatable element when inserting a coin in the coin slot, means to inhibit the rotation of the rotatable element when inserting a coin, said obstructing means comprising a spring urged member urged against the interponent and having a portion thereof normally blocking movement of the rotatable element, said obstructing means also being engageable by the coin when inserted and being movable thereby to a non-blocking position to free the rotatable element for movement by the coin, said interponent coin being releasable during movement of the rotatable element, and said inserted coin becoming the interponent coin when rotation of the rotatable element is terminated by the inhibiting means.
